WATER CLOSET SEAT COVER

David E. Harrison, Columbus, Miss., assignor to
Beneke Corporation, Columbus, Miss.

Filed Sept. 5, 1974, Ser. No. 503,914

Term of patent 14 years

Int. Cl. D23—02

U.S. Cl. D23—71

Fig-1

Fig-2

Fig-3

FIG. 1 is a plan view of the water closet seat cover embodying my new design.

FIG. 2 is a side elevational view thereof.

FIG. 3 is a cross-sectional view taken on line 3—3 of FIG. 1.

I claim:

The ornamental design for a water closet seat cover, as shown.
